UNITED STATES PATENT OFFICE

103,332

DESIGN FOR A REFRIGERATOR

Raymond Loewy, New York, N. Y., assignor to Sears, Roebuck and Co., Chicago, Ill., a corporation of New York

Application November 16, 1936, Serial No. 65,919

Term of patent 7 years

To all whom it may concern:

Be it known that I, Raymond Loewy, a citizen of France, residing at New York, in the county of New York and State of New York, have invented a new, original, and ornamental Design for a Refrigerator, of which the following is a specification, reference being had to the accompanying drawing, forming a part thereof.

The drawing is a perspective view of a refrigerator embodying my new design.

The side of the device not shown in the drawing is similar in appearance to the side which is shown.

I claim:

The ornamental design for a refrigerator, as shown and described.

RAYMOND LOEWY.
